LAST

Garrett P. S. Cross, Beverly, Mass., assignor to
 United Shoe Machinery Corporation, Paterson,
 N. J., a corporation of New Jersey

Application June 25, 1936, Serial No. 87,245

6 Claims. (Cl. 12—136)

This invention relates to hinge lasts of the im-
 positive lock type. Lasts of this type have a heel
 part and a forepart hinged together to permit
 a relative rotary movement between the parts in
 order to collapse the last. They are also provid-
 ed with a bonding mechanism between the parts
 which yields to pressure when the last is to be
 collapsed, but tends to restore the last parts to
 the positions from which they have been moved,
 10 at least until the movement has reached a sub-
 stantial magnitude. Many such lasts resiliently
 resist movement from either extended or col-
 lapsed position, and it is such a last that is dis-
 closed herein.

15 A number of lasts of this character have been
 provided with a resilient link connection between
 the last parts. Ordinarily this link joins two
 pins, one in each last part, and the center around
 which the last parts swing in collapse lies a
 20 little to one side of the line joining the centers
 of the pins so that when the last is collapsed the
 line passes over the center, the two last parts
 acting as toggle links. The collapsing movement
 causes the pins to separate a little, initially, thus
 25 stretching the resilient link until the dead center
 position is reached, and a slight movement either
 way from the dead center position will be auto-
 matically continued by the resilient action of the
 30 link, until fully extended or collapsed position is
 reached. In the same way the last automatically
 resists movement from either such position.
 Since the resilient link in such a last has to be
 very strong, the amount of stretch necessary in
 35 operating the last must be small in order to per-
 mit operation of the last by hand, as is custom-
 ary in shoemaking. Therefore the center of ro-
 tation of the last parts must not be far from the
 axis of the link, when the last is extended, in
 40 order to derive maximum advantage from the
 toggle action.

Lasts of this type have given difficulty when
 they are supported on their upper sides at the
 heel and toe and treated with pressure on the
 bottom, as in the leveling machine. The last
 45 parts then tend to rotate about the lower edges
 of the joint surfaces at which they are in con-
 tact, and such rotation, if it takes place, will
 stretch the link in the same way as above de-
 scribed in reference to the collapsing operation.
 50 The leveling pressure is often severe enough to
 effect a substantial overstretching movement of
 this kind, of sufficient magnitude to distort a
 shoe on the last, or to damage the last.

It has been proposed to alleviate this difficulty
 55 by mounting an inextensible link alongside the

resilient link, the extensible link having slotted
 ends to permit the pins to separate just enough
 to collapse the last, such separation being quite
 small, as above suggested. When the backward
 collapsing movement in the leveling machine be-
 5 gins, the inextensible link brings up firmly on the
 pins before any substantial movement has taken
 place, and rigidly holds the last against further
 movement of this sort. Such lasts are expensive
 10 because of this extra link, and labor cost in as-
 sembling.

The principal object of the present invention
 is to provide a last having the advantages of the
 type of last just described, but which is not sub-
 ject to the objection of added expense and com-
 plication. The resilient link according to the
 15 present invention is provided in itself with means
 to prevent its own overstretching, so that no
 extra parts are required. Conveniently, and as
 shown in the last herein illustrated, the link is 15
 formed in a generally elliptical shape, with its
 longer axis extending between the pins, so that
 the middle positions of its longer sides are
 brought closer together by the longitudinal
 stretching due to either of the movements dis- 20
 cussed above. The means for preventing over-
 stretching the link is shown as a lug or abutment
 on the inside face of the long side of the link
 which abuts against a surface on the opposite
 25 side of the link when the pins separate a little
 more than they have to do in the collapsing
 movement. As soon as this contact takes place,
 the link becomes inextensible unless sufficient
 force to break the last is applied.

These and other features of the invention com- 30
 prising certain combinations and arrangements
 of parts will be apparent from the following de-
 scription of a preferred embodiment of the in-
 vention shown in the drawing, in which

Fig. 1 shows the last in extended position; 35
 Fig. 2 shows the last in collapsed position; and
 Fig. 3 shows the action of the link in prevent-
 ing backward collapse.

The illustrated last consists of a forepart 10
 and a heel part 12 separated by a cut compris- 40
 ing a V-shaped opening 14 and a knuckle 16, as
 is well known in lasts of this character. The
 center 18 of the knuckle is the axis of the col-
 lapsing movement. The bonding mechanism
 comprises an open oval-shaped resilient link 20, 45
 which joins pins 22, 24, one in each of the last
 parts. As exaggeratedly shown in Fig. 1, the
 center 18 is a little above the axis 26 of the link
 20 so that the pins separate slightly in collapse
 50 and the link is correspondingly stretched, until
 the link is

the axis 26 passes to the other side of the center 18 (Fig. 2). Until the axis 26 of the link crosses the center 18 the last parts tend to return to the position from which they have been moved, either extended or collapsed.

5 The central part of the link 20 is provided with two opposed lugs 28, one on each side. The lengths of these lugs 28 are such that they do not quite touch when the last is extended or collapsed (Figs. 1 and 2), or in any intermediate position. When the last is stressed in such a way as to bend it backwards, as is exaggeratedly shown in Fig. 3, only a very slight rotary movement about the point 30 can take place before the lugs 28 10 come firmly together (Fig. 3). Such movement is considerably less than the movement involved between the extended (or collapsed) position and the dead center position because the point 30 is considerably farther from the axis 26 of the link 20 than is the center 18, and a correspondingly smaller rotary movement about the point 30 will stretch the link to its limit, where the lugs 28 render it substantially rigid.

25 The bonding mechanism described above consists of only three members, one link and two pins, and is correspondingly cheap, easy to assemble, and simple and effective in operation.

Having described my invention, what I claim as new and desire to secure by Letters Patent of the 30 United States is:

1. A hinge last comprising a heel part and a forepart arranged for relative rotation about an axis fixed in the last, a resiliently extensible link joining said last parts, and means on the link to prevent overstretching thereof.

35 2. A hinge last comprising a heel part and a forepart arranged for relative rotation about an

axis fixed in the last, a resiliently extensible link pivotally joining said last parts, the longitudinal axis of the link lying between the first said axis and the tread face of the last, and means on the link to prevent stretching thereof substantially beyond the extent necessary to permit collapse of the last.

3. A hinge last comprising a heel part and a forepart arranged for relative rotation about an axis fixed in the last and a resiliently extensible 10 oval-shaped open link joining said last parts, the longitudinal axis of the link lying between the first said axis and the tread face of the last, said link having a lug on the inside face of one of its longer sides arranged to contact with a surface 15 on the opposite longer side before the link has been stretched substantially to a greater extent than that involved in collapsing the last.

4. A resiliently extensible link for a hinge last, said link being of open oval shape with its long 20 axis lying in the direction of extension and having a lug on one of the inner faces of its opposite longer sides, said lug terminating adjacent to a surface on the inner face of the opposed longer side.

25 5. A resiliently extensible link for a hinge last, said link being of open oval shape and having opposed lugs on the inner faces of its opposite longer sides, said lugs having a free space between them sufficient to permit stretching the link only 30 to the desired amount.

6. A resiliently extensible link for a hinge last, said link being of open oval shape with its long axis lying in the direction of extension and having opposed lugs on the inner faces of its opposite 35 longer sides.

GARRETT P. S. CROSS.
